UNITED STATES PATENT OFFICE.

WILLIAM WALTER HARTMAN, OF LOS ANGELES, CALIFORNIA.

PACKER.

Application filed May 16, 1925. Serial No. 30,727.

An object of my invention is to provide a swab with an improved packer which will efficiently lift or swab fluid from oil or water wells, and also be very durable under 5 heavy loads so that the packers need not be so frequently replaced as at present.

Another object of my invention is to provide a packer which will resist much of the longitudinal distortion that the packer is 10 ordinarily subjected to by the load.

Another object of my invention is to provide a packer made of relatively flexible material, but so reinforced by a metallic reinforcement as to permit radial expansion between 15 its extremities but to resist longitudinal compression.

Some features of my invention are applicable to pistons generally and may be used in pumps as well as swabs. This is particularly true of my general form of reinforced packer, which I desire to protect broadly as to all its uses.

Other objects, advantages and features of invention may appear from the accompanying drawings, the subjoined detailed description and the appended claims.

The accompanying drawings illustrate the invention.

Figure 1 is a side elevation of my swab, 30 with parts broken away and with the casing shown in section.

Fig. 2 is a longitudinal sectional view of my swab on a slightly smaller scale and showing some additional parts not shown 35 in Fig. 1.

Fig. 3 is a sectional view taken on line x^3 , Fig. 1.

Fig. 4 is a sectional view on line x^4 , Fig. 2.

Fig. 5 is an elevation of a modified form 40 of my packer shown with some of its cooperating parts.

Fig. 6 is a longitudinal sectional view of my swab equipped with the modified packer shown in Fig. 5, and with some parts of 45 the swab broken away.

Fig. 7 is a sectional view on line x^7 , Fig. 6.

Fig. 8 is a sectional view on line x^8 , Fig. 6.

The usual tubing or well casing 1 is made 50 in sections having couplings 2 provided therein.

The top of my swab may be formed with a threaded coupling head 3 adapted to screw into the lower end of the usual string of tools. These tools are not shown in the 55 drawings because they are well known well rig equipment. A bolt 4 threads into the

bottom of the coupling head 3 and is provided with a head 5.

The bolt loosely extends through the end of a sleeve 6 which swivels on the head 5. 60

A plurality of ports 7 extend through the side of the sleeve. At its lower end the sleeve 6 is fastened to a stem or pipe 8, which depends therefrom, and a ball check 9 seats on an appropriate seat, which may be 65 the top of pipe 8 as shown.

A tip or guide 10 is threaded to the bottom of the pipe 8, the outer surface of which may be suitably tapered to guide the swab 70 in the well.

A packer 11 is mounted on pipe 8 as shown in the figures.

The purpose of this packer is to act as a seal, and I prefer to make it of some flexible material like rubber, fabric, leather or the like. Also though the packer may have any general shape to suit the tastes of the designer or user, yet I prefer a packer having one or both ends of reduced diameter so that the metallic end plates 12 may be preferably cup shaped, as shown in Figs. 1, 4, 5 and 6. 75

The form of cup that I have shown on the drawings circumferentially embraces the packer at its extremity and resists expansion of the packer radially at the extremity. If an upper cup is used it may have some arrangement about it that will allow fluid to freely pass into the internal bore of the packer to expand the latter by fluid pressure 90 during operation, and the provision which I have shown for this purpose includes the radial fluid grooves 13 and the circumferential groove 14 on the upper face of this cup, which, in conjunction with the fact 95 that the bore 15 of this cup may be a little larger than pipe 8, and that flutes or grooves 16 may be formed in pipe 8, produces an obvious channel whereby the fluid above the packer may transmit its pressure to the inside of the packer to expand it. 100

Other modes of introducing this fluid into the packer may be used, but I have found the above quite suitable. If the packer and upper cup should for any reason rise till the top of this cup contacts with the lower face of sleeve 6, the fluid can still find its way through the channel into the bore of the packer.

Though I am aware that the lower cup 110 can be formed the same as the upper cup, excepting perhaps that the grooves 13

should be omitted, nevertheless I prefer to arrange the lower cup a little differently. At the place where the pipe or stem 8 passes through the lower cup I prefer to reduce 5 the diameter of the stem so as to form a downwardly facing shoulder 17, and the stem may be threaded from a point below this shoulder to the lower extremity. The hole in the lower cup is then made small 10 enough so the cup seats against the shoulder 17, and nut 18 and lock nut 19 are provided for securely holding this cup up against this seat or shoulder; and for supporting the load during operation.

15 In connection with packer 11, and preferably embedded therein, I provide a metallic reinforcement 20, constructed to permit radial expansion of the packer for allowing effective sealing, and yet constructed to resist longitudinal compression and distortion 20 of the packer under load.

Packers not having such metallic reinforcement for resisting the longitudinal distortion caused by the load, wear and cut out 25 rapidly at the bottom just above the lower cup or equivalent part.

The reason for this appears to be that the weight of the load plus the excessive friction which a longitudinally compressed 30 packer sets up while rising through the well tubing or casing 1, has a peculiar accumulating compressive action which soon wears or cuts the packer away at the bottom.

I have discovered that a metallic reinforcement can be embedded in the packer in such manner as to resist this longitudinal compression and distortion, and when this is done it either completely eliminates or else greatly retards the cutting or wearing 40 away of the packer at the bottom.

To reinforce against longitudinal compression is perhaps more important than to provide for automatic radial expansion by the fluid pressure, as the packer can be shaped a little differently than I have shown and made of sufficient diameter to nicely fill and seal the tubing 1, and such a packer, with the metallic reinforcement, will be quite durable and effective, without radial fluid expansion, although I prefer the latter feature as it is more positive in its sealing action.

My invention of a metallic reinforcement embedded in the packer for resisting and 55 minimizing longitudinal or vertical distortion, is broadly new, and results in greatly increasing the life and durability of such packers, thereby decreasing the expense and annoyance of replacing them so frequently.

60 The precise form of this metallic reinforcement can be varied to suit the tastes of the designer, and although I have here illustrated my preferred form of reinforcement, it is understood that other forms including 65 the modifications thereof shown in my co-

pending application filed April 27th, 1925, Serial Number 26,171, to which reference is hereby made, may be employed with satisfactory results.

The form herein shown consists of a looped wire the general shape of which is apparent from the drawings, and the wire is of sufficient stiffness to give the desired reinforcing strength. This form has the advantage of being simple and cheap to make, and in addition it is stiff vertically, but somewhat flexible radially in view of its length, a condition which is also true of the modified reinforcements shown in my above mentioned copending application. 70 75 80

It also can be nicely moulded into the packer, allowing the packer material to be continuous all around each vertical leg or the wire, and this together with the full thickness of the packer at its center of height, 85 gives a united construction resulting in a durable packer with lots of material to withstand the slow gradual rate at which it now wears.

The form of packer shown in Figs. 1 and 2 90 is symmetrical, and therefore after running it in one position for a considerable time it can be turned upside down and run a considerable time longer in such reverse position. 95

The form of packer shown in Figs. 5, 6, 7 and 8, is a little different, a ring 21 being used in place of the cup shown in Figs. 1 and 2; also the top of the metallic reinforcement 20 is below the level of this ring, which permits a little freer radial expansion if that should be desired, and the bottom of the reinforcement may come down close to the bottom of the packer. Also if the expedient of internal fluid expansion for the 100 105 packer is used, the fluid may be given free access to a large portion of the internal surface of the packer by coring the same out for a distance between its ends as shown at 22, Fig. 6, in place of making the entire bore of 110 the packer of slightly larger diameter than the pipe 8, as shown at 23, Fig. 2. These and other alternative or equivalent modifications can be used interchangeably as may be desired. 115

In operation the swab is lowered into the well and into the fluid standing therein. The liquid passes upwardly through guide 10, pipe 8, past the ball 9, and through ports 7 out into that portion of the casing or tubing 1 which is above the swab. In an obvious manner some of this fluid will settle back through grooves 16 in pipe 8 into the inside of packer 11, and when the swab is raised all the fluid above it will be lifted. The pressure of this fluid will then be transmitted to the inside of the packer expanding same till it seals the casing, if it does not already do so. By lifting the swab to the top of the well, the entire column of fluid 120 125

above it is ejected from the well, after which the swab is again lowered for the purpose of bringing up another load, and so on in accordance with usual swabbing procedure.

5 Subject matter of invention shown but not claimed in this application is reserved and claimed in my above said copending application Serial Number 26,171, filed April 27, 1925, to which reference is hereby made.

10 I claim:

1. A packer having a hole passing axially therethrough and an exterior surface elongated in the direction of said axis, and metallic reinforcing means molded into said 15 packer to form a part thereof, said metallic reinforcing means having a longitudinally rigid lengthwise portion extending substantially parallel to the axis of said packer and terminating short of the forward extremity 20 of said packer to make same strong longitudinally.

2. A packer having a hole passing axially therethrough and an exterior wearing portion, said packer being adapted to expand 25 radially when fluid pressure is applied to its inner surface, and metallic reinforcing means permanently embedded in said packer to make same strong longitudinally, said metallic reinforcing means having a longitudinally rigid lengthwise portion extending substantially parallel to the axis of said 30 packer and having a supporting shoulder embedded in said packer below the forward extremity thereof to effectively resist compression of that extremity toward the opposite extremity during the operation of the packer.

3. A packer having a hole passing axially therethrough, metallic reinforcing means 40 permanently embedded in said packer and comprising wire looped back and forth between the ends of said packer in a practically continuous path around said packer.

4. A packer having a hole passing axially 45 therethrough, reinforcing means permanently embedded in said packer and comprising wire looped back and forth between the ends of said packer in a practically continuous path around said packer, said packer being

substantially symmetrical about a plane 55 passing centrally through it at right angles to its axis.

5. A packer having two ends, a hole passing axially therethrough and an exterior wearing portion, and reinforcing means permanently embedded in said packer comprising elongated loops of wire terminating short of one end of said packer to make the 60 packer strong longitudinally.

6. A packer having two ends, a hole passing axially therethrough and an exterior wearing portion, and metallic reinforcing means permanently molded into said packer and comprising wire looped back and forth between the ends of said packer to make 70 same strong longitudinally.

7. A packer having a hole passing axially therethrough, two ends and an exterior wearing portion, and metallic reinforcing means permanently embedded in said packer, 75 said reinforcing means comprising elongated loops of wire lengthwise embedded in said packer between the two ends thereof.

8. A packer having a hole passing axially therethrough, said packer being of reduced 80 external diameter at both ends and having an exterior wearing portion of enlarged diameter approximately midway between said ends, and a radially yieldable but longitudinally stiff metallic reinforcing means 85 permanently imbedded in said packer between its ends.

9. A packer having a hole passing axially therethrough, said packer being of reduced external diameter at both ends and having 90 an exterior wearing portion of enlarged diameter approximately midway between said ends, and a longitudinally stiff metallic reinforcement permanently imbedded lengthwise in said packer and terminating short of 95 the end thereof, said reinforcement being adapted to make said packer strong longitudinally.

In testimony whereof, I have hereunto set my hand at Los Angeles, California, this 100 8th day of May, 1925.

WILLIAM WALTER HARTMAN.
